CLARENCE CARSON, OF DETROIT, MICHIGAN.

HORN.

1,107,654.

Specification of Letters Patent. Patented Aug. 18, 1914.

Application filed May 12, 1913. Serial No. 766,935.

To all whom it may concern:

Be it known that I, CLARENCE CARSON, a citizen of the United States, and a resident of Detroit, in the county of Wayne and State of Michigan, have invented a new and Improved Horn, of which the following is a specification.

This invention relates to means for producing sounds through the agency of an alternating electric current, and its object is to provide an effective horn which may be constructed at low cost and which shall have no spark gaps.

This invention consists, in combination with a bell, a diaphragm and a case, of an electro-magnet having poles formed of substantially U shaped wires with all ends in the same plane and positioned with their legs on both the outer and inner sides of a spool of insulated wire, of an armature adapted to be attracted by said poles, and resilient means to force the armature against the diaphragm.

In the accompanying drawing, Figure 1 is a central longitudinal section of this improved horn. Fig. 2 is a view showing the wires arranged to form the poles. Fig. 3 is a diagram of currents.

Similar reference characters refer to like parts throughout the several views.

The bell 1 of this horn may be of any desired construction, and the diaphragm 2 is mounted between the bell and the case 3 in the usual manner. A cap 4 fits over the head of the case and has a central opening for the current wires 5 and 6 that connect to the binding posts 7 and 8, mounted in the head 9 of the case.

The electro-magnet is of peculiar construction and consists of a body 11 of gutta-percha, hard rubber, or any other of the many suitable non-conducting non-magnetic materials which can be baked hard at temperatures below that at which the fibrous insulation of the wires of the spool 12 will be destroyed. This spool may connect to the binding posts 7 and 8 by means of wires 13 and 14. The poles of this electro-magnet are composed of pieces of soft wire, forming the outer legs 15 placed outside the spool 12 and the inner legs 16 within the spool, connected by the radial parts 17. The ends of the inner legs 16 may be bent outwardly toward the ends of the outer legs, as shown

in Fig. 1. The spool 12 is placed between the poles, the ends of the inner legs bent outwardly, and these parts are then placed in a proper mold, after which the insulating material 11 is poured around the wires, and then baked. The extension 19 may be formed on the body 11 if desired or it can be made separately of any desired material and then united with the body 11. The head 9 is preferably formed with an annular flange 20, which, together with the extension 19, may be threaded to fit each other, so that the electro-magnet may be adjusted with reference to the diaphragm 2, a jam nut 21 being employed to lock the parts in position.

The body 11 and extension 19 are drilled and the latter threaded to receive the adjusting screw 23 which tensions the spring 24 that bears on the ball 25, and presses it toward the diaphragm. The ball bears against the end of the stem 26 on which is a disk 27 of soft iron, while on the disk is a projection 28 which normally contacts with the diaphragm 2.

Under normal non-active conditions, the spring 24 holds the projection against the diaphragm 2 and prevents any rattling of the parts. When an alternating current passes over the wires 5 and 6, especially a current from a magneto, the poles 15 and 16 will become alternately magnetized and demagnetized, the polarity of the poles reversing at each new magnetization. Thus when the current is negative, or below the line A in Fig. 3, the outer pole, or wires 15 may become magnetically positive and the inner pole or wires 16 magnetically negative. When the current is changing, or crossing the line A, the poles become demagnetized, and when the current becomes positive, or above the line A, the polarity of the poles will be the reverse of what it was before the change in the current.

At each magnetization of the poles, the armature 27 will be attracted by the electro-magnet, and at each demagnetization prior to a change of polarity, the armature will be released by the poles and forced against the diaphragm 2 by the spring 24. As soon as the electro-magnet is again energized, the armature is again drawn away from the diaphragm. The result of such striking of the diaphragm by the projection 28 is a

sound which may be a musical note if the alternations of the current are sufficiently rapid.

I claim.

- 5 1. In a horn, the combination of a bell, a case having a base flange, a diaphragm between the bell and the flange of the case, a cylindrical body of non-conducting and non-magnetic material mounted in said case, a 10 spool of wires embedded therein, a series of substantially U-shaped magnetic wires within said body having their legs within and without the spool to form two circular poles in the face of the body adjacent the diaphragm, a stem slidable in said body at 15 right angles to the diaphragm, an armature on the stem between the body and diaphragm, a spring within the body to force the stem against the diaphragm and wires 20 to conduct current to said spool.

2. In a horn, the combination of a case, a bell and a diaphragm between them, a cylindrical electro-magnet mounted in the case with its axis at right angles to the diaphragm and having two circular poles at 25 the end adjacent the diaphragm, an armature for the magnet and a guide therefor, means for forcing the armature into contact with the diaphragm, and electric wires connecting directly with a source of alternating 30 current and with the winding of said electro-magnet.

3. In a horn, the combination of a diaphragm, an electro-magnet having an annular spool, and poles in one end adjacent to and parallel to said diaphragm, an armature for the magnet between the poles and diaphragm, a guide for the armature, means to force the armature against the diaphragm, and uninterrupted means to conduct an alternating current to the spool of 40 the magnet.

4. In a horn, the combination of a case, a diaphragm, an electro-magnet having its 45 two poles in one end adjacent the diaphragm

and a spool between said poles, an armature for the magnet between the poles and diaphragm, a spring to force the armature against the diaphragm, said case, diaphragm, magnet poles, spool, armature and 50 spring all being concentric with each other, and a pair of wires extending through an opening in said case and connecting to said spool.

5. In a horn, the combination of a bell, a case to support the bell, a diaphragm between the bell and case, a cylindrical body of non-conducting and non-magnetic material mounted in said case, a spool of wires embedded therein, a series of substantially 60 U shaped magnetic members embedded in said body with their legs within and without the spool to form two circular poles in the face of the body adjacent the diaphragm, a stem slidable in the body, an armature on 65 the stem between the body and diaphragm, and a spring to force the stem against the diaphragm.

6. In a horn, the combination of a bell, a case to support the bell, a diaphragm between the bell and case, a cylindrical body of non-conducting and non-magnetic material mounted in said case, a spool of wires embedded therein, a series of substantially 70 U shaped magnetic members embedded in 75 said body with their legs within and without the spool to form two circular poles in the face of the body adjacent the diaphragm, a stem and armature adapted to be moved away from the diaphragm by the 80 magnetic poles, and means to force the stem against the diaphragm.

In testimony whereof I have signed this specification in the presence of two subscribing witnesses.

CLARENCE CARSON.
